UNITED STATES PATENT OFFICE.

BRYSON D. HORTON, OF DETROIT, MICHIGAN, ASSIGNOR TO SQUARE D COMPANY, OF DETROIT, MICHIGAN, A CORPORATION OF MICHIGAN.

ELECTRICAL SWITCH INCLOSURE OR CABINET.

Application filed June 16, 1922. Serial No. 568,877.

To all whom it may concern:

Be it known that I, BRYSON D. HORTON, a citizen of the United States, residing at 6060 Rivard Street, Detroit, in the county 5 of Wayne and State of Michigan, have invented new and useful Improvements in Electrical Switch Inclosures or Cabinets, of which the following is a full, clear, concise, and exact description, reference being had 10 to the accompanying drawing, forming a part of this specification.

This invention relates to an electrical switch inclosure or cabinet, and more particularly to an improved form of cabinet 15 knock-out and trough fastening means.

In practice, when a plurality of service entrance switch cabinets are positioned in close proximity, it frequently becomes desirable and necessary to run conductors from 20 one cabinet to the other, and in this case it has been found convenient to lead these wires through suitable troughs, especially designed for this purpose, which may be connected to knock-out openings in the walls 25 of the switch inclosure or cabinet. The troughs utilized for this purpose are ordinarily of a U-shape, and in connecting these troughs to the box it is essential that the boxes be bonded together electrically, and 30 consequently the connection between the troughs and the cabinets or inclosures must be a positive electrical contact.

The troughs used for this purpose have ordinarily been connected to the U-shaped 35 knock-out opening in the cabinet or inclosure by bolts and nuts which pass through holes drilled in the cabinet adjacent the U-shaped knock-out opening. These holes provided in the cabinet for this purpose are very 40 objectionable since they provide an opening through which the inexperienced might and can insert wires or other foreign substances which might result in short-circuits, arcing, etc., which would seriously damage 45 the apparatus connected to the circuit.

It is one of the objects of this invention, therefore, to provide an improved means of knock-out in which there is no opening in the box through which foreign substances 50 may be inserted. In the improved form, the opening utilized to connect the trough to the box is part of the cabinet knock-out and is completely closed when the trough is in position by the trough itself and the accompanying trough fastening means,

Another object of the invention consists of the provision of improved means for obtaining positive and good electrical contact between the cabinet wall and the trough.

Other objects of the invention will become 60 apparent from the following description; the accompanying drawings, and the appended claims.

For the purpose of description, a preferred form of the invention is illustrated 65 in the accompanying drawings in which—

Figure 1 is a plan view of two service switch inclosures interconnected by a trough;

Fig. 2 is a side elevation of the side wall 70 of an inclosure, and illustrates the method of connecting the trough to said wall;

Fig. 3 is a plan view of two walls of the switch inclosure interconnected by the trough with the covers of the switch re- 75 moved;

Fig. 4 is a section taken on the plane represented by the line 4—4 of Fig. 3;

Fig. 5 is a cross-section taken on the plane represented by the line 5—5 of Fig. 4; 80

Fig. 6 is a side elevation of the wall of the inclosure showing the form of the trough knock-out;

Fig. 7 is a sectional view taken on the plane represented by the line 7—7 of Fig. 4; 85

Fig. 8 is a side view of another form of trough and interconnecting means between the trough and the cabinet in which the cover of the trough is broken away to clearly show the method of cabinet and trough interconnection;

Fig. 9 is a side elevation of the inside wall of the cabinet showing in detail the means for interconnecting the type of trough illustrated in Figure 8 to the wall of the 95 cabinet;

Fig. 10 is a sectional view taken on the plane represented by the line 10—10 of Figure 8;

Fig. 11 is a sectional view taken on the 100 plane represented by the line 11—11 of Figure 9, looking in the direction of the arrows, and illustrates the foot used to connect the trough to the side wall of the cabinet and the interconnecting means; 105

Fig. 12 is a side elevation of the inside wall of the cabinet showing another preferred form of trough interconnecting means;

Fig. 13 is a plan view of two walls of the 110

switch inclosure interconnected by the trough with the cover of the trough slightly broken away and utilizing the trough interconnecting means of Figure 12;

5 Fig. 14 is a section taken on the plane represented by the line 14—14 of Figure 12;

Fig. 15 is a sectional view taken on the plane represented by the line 15—15 of Figure 12;

10 Fig. 16 is a side elevation of the wall of the inclosure showing the form of trough knock-out utilized with the preferred embodiment thereof illustrated in Figures 12 and 13;

15 Fig. 17 is a section taken on the line 17—17 of Figure 14; and,

Fig. 18 is a sectional view taken on the line 18—18 of Figure 14.

20 The trough used to carry the wires from one service entrance switch cabinet to the other, when these service switch cabinets are mounted in a row in close proximity, is preferably interconnected between these cabinets in the manner illustrated in Figure 1. As there shown, the cabinets or inclosures 15 and 16 are interconnected by a through 17. The switches are preferably provided with covers and with exterior operating handles such as 18.

25 30 The trough 17 comprises a U-shaped part 19 and a cover 20 (see Fig. 3). The U-shaped portion 19 is fitted at each end with flanges such as 21 and 22, the flanges 21 and 22 serving to inclose the edge of the trough

35 knock-out provided in the side wall such as 23 and 24, respectively, of the cabinets. The trough knock-out provided in the side walls of the cabinet, such as 23, is of a U-shaped form to fit the part 19 of the trough. This

40 U-shaped knock-out is fitted with an indenture 25, preferably V-shaped, which indenture serves to receive the means for securing the trough to the side wall of the cabinet. Adjacent to the outer edge of this V-shaped

45 indenture is an upset projection 26. This upset projection is utilized to compensate for the thickness of the flange 21 of the trough 17 when said trough is connected to the cabinet by the interconnecting means to be hereinafter described, and also serves to insure positive electrical contact between the trough and the wall of the switch inclosure or cabinet.

50 55 As illustrated in Figures 4 and 5, the trough 17 is preferably connected to the side wall of the cabinet by means of a bolt such as 27 and its cooperating washer 28 and nut 29. The bolt 27 is inserted through the V-shaped indenture 25 between the edge

60 of the flange 21 of the U-shaped part 19 of the trough 17 and the upset projection 26, as clearly illustrated in Figures 4 and 5. When the bolt 27 is thus inserted in place

65 to fasten the trough to the side wall 23 of the cabinet, the flange 21 of the trough, to-

gether with the head of the bolt 27, completely cover the V-shaped indenture 25, so that access to the interior of the cabinet is not possible.

As illustrated in Figure 5, the upset projection 26 is displaced a distance just equal to the thickness of the flange 21 of the trough 17, whereby the washer 28 and the nut 29 will rest against a surface substantially parallel to the side wall of the cabinet. 70 When the nut 29 is screwed home on the bolt 27, the washer will bind the flange 21 between itself and the side wall of the cabinet, and the washer will also be forced against the edge of the upset projection 26. 75 When the nut 29 has thus been screwed up tight, the trough 17 is firmly held in place and electrical contact between the trough and the cabinet is insured through the contact between the washer and the edge of the 80 upset portion 26. To make this electrical contact more positive, the enamel is preferably scraped from the edge of the upset projection 26 before the nut and washer are tightened up to secure the trough to the 85 cabinet.

As will be evident from the foregoing description, the knock-out for the trough in the cabinet, according to the teachings of this invention, is fitted with an indenture 90 which serves as a means for receiving the bolt and nut used to secure the trough to the side of the cabinet. This indenture is removed from the wall of the cabinet with the trough opening at the time that it is 95 desired to place the trough in position. This results in the advantage that no openings are normally maintained in the cabinet for securing the trough thereto when a trough is desired. It has been the customary practice to provide in switch inclosures of this character in which troughs might be used an aperture at the side of the trough-opening through which the bolt is positioned after the trough knock-out has been 100 displaced and the trough put in position. This aperture originally provided in the switch inclosure has been the means of considerable trouble due to the insertion of foreign matters by the inexperienced 105 through the aperture. This trouble is entirely eliminated by the new form of knock-out and trough interconnection hereinbefore described.

110 The improved construction described, in addition to avoiding this aperture in the side of the switch inclosure, provides a more positive means for obtaining a good electrical connection between the trough and the cabinet as hereinbefore described.

115 Figures 8, 9, 10 and 11 illustrate another form of trough interconnection. The form of trough knock-out used with this modified form of trough interconnection is the same as that illustrated in Figure 6. In the modi- 120

fied form, as illustrated in the figures, the trough is equipped with a foot 32 provided with an aperture which receives the bolt 33 that passes through the wall of the cabinet 34 and is held in position by the nut 35. The trough is fitted with a flange 36, which carries a cut-out portion 37. This cut-out portion 37 is designed to receive the nut 35 and prevent it from turning when the bolt 33 is drawn up tight.

In this construction the trough is slipped into position, as illustrated in Figures 8 and 11, after which the nut 35 is positioned in the cut-out portion 37, and thereafter the bolt is passed through the foot 32 and into the nut and drawn up tight. When the bolt and nut have thus been drawn up tight, the bolt is positively positioned and electrical contact is obtained between the surface of the nut which is in contact with the wall of the cabinet. To insure this electrical contact the enamel is removed from the face of the wall where this contact is made.

In the preferred form of trough interconnection, illustrated in Figures 12 to 18, inclusive, the trough is interconnected to the side of the cabinet by means of a suitable clip or bracket 40, which serves to ride over the edge of the flange 41 of the trough (see Figure 12) and thus hold the trough in place. The clip or bracket 40 is provided with two forwardly projecting arms 42 and 43 (see Figure 14), the arm 42 resting on the inner surface of the trough and the arm 43 resting in the depression 44 positioned in the side wall of the switch inclosure, as clearly illustrated in Figure 14. The upset portion of the side wall of the switch inclosure, which furnishes the depression 44 in which the arm 43 rests, is positioned directly beneath the V-shaped cut-out or indenture 45 which extends from the U-shaped trough knock-out 46. The clip or bracket 40 is preferably held in position on the side wall of the switch by means of a screw such as 47.

As will be evident from the illustrations, the clip or bracket 40, when screwed into position, as illustrated in Figure 14, serves to hold the trough in its position in the side wall and also prevents raising of the trough out of its set position in the lower part of the trough knock-out. This raising of the trough is prevented by the arm 43 which rests in the depression 44 which serves to hold the clip or bracket 40 in the position with its arm 43 in said depression, and consequently also serves to hold the trough in its normal position in this side wall knock-out.

In the preferred form of trough interconnection, illustrated in Figures 12 to 18, inclusive, the trough is inserted into the side wall of the switch by first removing the U-shaped trough knock-out with the V-

shaped indenture 45. The trough is then slipped into position and the clip or bracket 40 positioned in place with its arm 43 in the depression and the arm 44 riding on the inside surface of the trough. The holding-screw 47 is then screwed into position and when screwed up tight will hold the trough in its lowermost position in the knock-out, from which position it cannot be raised unless the clip or bracket 40 is loosened so as to permit the arm 42 to ride out of the depression 44.

In this form of trough interconnection good electrical contact is obtained between the side of the switch box and the clip at the point where the arm 43 of the clip rides in the depression 44, and at the point where the clip or bracket 40 rides over the edge 50 of the trough. Consequently, with this type of interconnection, positive electrical contact is insured between the trough and the switch housing.

It will be evident from the foregoing description that with the construction of trough and trough interconnection illustrated and described, the usual openings normally provided in the cabinet for connecting the trough thereto are avoided and an improved form of construction is furnished to insure electrical contact between the trough and the cabinet. These advantages are obtained in a construction which is simple and easy to manufacture and consequently without any additional manufacturing expense.

Obviously, the invention is not limited to the specific embodiment thereof hereinbefore illustrated and described, but is capable of many variations within the scope and spirit of the invention as set out in the appended claims.

What I now claim as new and desire to secure by Letters Patent from the United States is:

1. In a device of the character described, in combination, a U-shaped trough, the wall of a switch inclosure comprising, a U-shaped trough knock-out, an indenture extending into the side of said wall from the edge of said U-shaped knock-out, and means extending through said indenture which serves to fasten said trough to said wall.

2. In a device of the character described, in combination, a U-shaped trough, the wall of a switch inclosure comprising, a U-shaped trough knock-out, a V-shaped indenture extending into the side of said wall from the edge of said U-shaped knock-out, and means extending through said V-shaped indenture serving to fasten said trough to said wall.

3. In a device of the character described, in combination, a U-shaped trough, the wall of a switch inclosure comprising a U-shaped trough knock-out, an indenture ex-

tending into the side of said wall from the edge of said knock-out, an upset projection extending from the wall of said inclosure adjacent the outer edge of said indenture, 5 and means extending through said indenture serving to fasten said trough to said wall, said means cooperating with said projection to make positive electrical contact between the wall and said trough.

10 4. In a device of the character described, in combination, a U-shaped trough, a flange on said trough, the wall of a switch inclosure comprising, a U-shaped trough knock-out, an indenture extending into the side of 15 said wall from the edge of said U-shaped knock-out, means extending through said indenture serving to fasten said trough to said wall, said means and the flange of said trough substantially closing the indenture 20 opening.

5. In a device of the character described, in combination, a U-shaped trough, a flange on said trough, the wall of a switch inclosure comprising, a U-shaped trough knock-out, an indenture extending into the side of 25 said wall from the edge of said U-shaped knock-out, means extending through said indenture serving to fasten said trough to said wall, said means and the flange of said 30 trough substantially closing the indenture opening, and an upset projection extending from the wall of said inclosure adjacent the outer edge of said indenture, said projection and said means cooperating to make 35 positive electrical contact between the trough and the cabinet.

6. In a device of the character described, in combination, a U-shaped trough, the wall of a switch inclosure comprising, a U- 40 shaped trough knock-out, a V-shaped indenture extending into the side of said wall from the edge of said U-shaped knock-out, an upset projection extending from the wall of said inclosure adjacent the outer edge of 45 said indenture, a bolt passing through said V-shaped indenture, a flange on said trough covering a portion of said V-shaped indenture adjacent said bolt, and means cooperating with said bolt to secure said trough 50 to the inclosure wall, which means cooperates with the said projection to obtain electrical contact between the inclosure and the trough.

7. In a device of the character described, 55 in combination, a U-shaped trough, the wall of a switch inclosure comprising, a U-shaped trough knock-out, an indenture extending into the side of said wall from the edge of said U-shaped knock-out, a flange on said 60 U-shaped trough positioned on the inside of said wall, an upset projection positioned on said wall adjacent the outer edge of said indenture, and means for securing said trough to said wall of the inclosure, said means 65 cooperating with the said projection to re-

tain the trough in position and to obtain positive electrical contact between the cabinet and the trough.

8. In a device of the character described, in combination, a trough, a flange secured to 70 said trough, and the wall of a switch inclosure comprising a trough knock-out, an upset projection extending from said wall which provides a slot in the inside of said wall, and means passing through said wall 75 for securing the trough to the wall through the agency of the flange and the said slot.

9. In a device of the character described, in combination, a trough, a flange secured to 80 said trough, the wall of a switch inclosure comprising a trough knockout, an upset projection extending outwardly from said wall and which provides a recess on the inside of said wall, and a bracket spanning said wall and flange between said recess and 85 the inside of said trough, said bracket serving to hold said trough in position in said wall of said switch inclosure.

10. In a device of the character described, in combination, a trough, a flange secured to 90 said trough, the wall of a switch inclosure comprising a trough knock-out, an upset projection extending outwardly from said wall and which provides a recess on the inside of said wall, a bracket spanning said 95 wall and flange between said recess and the inside of said trough, said bracket serving to hold said trough in position in said wall of said switch inclosure, and means for holding said bracket in position, whereby said trough cannot be raised from the bottom of 100 said trough knock-out.

11. In a device of the character described, in combination, a trough, a flange secured to 105 said trough, the wall of a switch inclosure comprising a trough knock-out and a V-shaped indenture extending into the side of said wall from the edge of said trough knock-out, an upset projection extending outwardly from said wall adjacent the edge 110 of said V-shaped indenture to form a depression in said wall, and a bracket cooperating with said depression to hold said trough in said trough knock-out, whereby said trough cannot be removed from said knock-out without the removal of said bracket.

12. In a device of the character described, in combination, a trough, a flange secured to 120 the trough, and the wall of a switch inclosure comprising a trough knock-out, a portion of said wall being removable with said knock-out to provide a passage for fastening means, and clamping means extending across said last opening and holding said trough in desired relation with said wall.

13. In a device of the character described, in combination, a trough, a flange secured to the trough, and the wall of a switch inclosure comprising a trough knock-out, a 130

portion of said wall being removable with
said knock-out to provide a passage for fas-
tening means, a clamping means extending
across said last opening and one end thereof
5 overlying said trough flange, and fastening
means for holding said clamping means in
desired relation.

14. In a device of the character described,
in combination, a trough, a flange secured to
10 the trough, and the wall of a switch inclo-
sure comprising a trough knock-out, a por-
tion of said wall being removable with said
knock-out to provide a V-shaped indenture,
clamping means comprising a member having

angularly-bent portions at its ends, a depres- 15
sion formed in said wall, and securing means
passing through said indenture to hold said
clamping means in desired relation with one
end of the latter overlying the trough flange
and the other end positioned in said depres- 20
sion whereby said trough is held in said
knocked-out portion against removal there-
from, said clamping means, when in opera-
tive position, completely covering said in-
denture. 25

In witness whereof, I have hereunto sub-
scribed my name.

BRYSON D. HORTON.
